UNITED STATES PATENT OFFICE.

HIRAM PLUMMER, OF BROOKLYN, NEW YORK, ASSIGNOR TO HIMSELF AND
WM. E. DOUBLEDAY & CO., OF NEW YORK CITY.

IMPROVEMENT IN SEWING-MACHINES.

Specification forming part of Letters Patent No. 93,553, dated August 10, 1869.

To all whom it may concern:

Be it known that I, HIRAM PLUMMER, of Brooklyn, in the county of Kings and State of New York, have invented, made, and applied to use a certain new and useful Improvement in Feeds for Sewing-Machines; and I do hereby declare the following to be a full, clear, and exact description of the said invention, reference being had to the annexed drawing, making part of this specification, wherein—

Figure 1 is a vertical section, illustrating my improved feed as applied to a sewing-machine. Fig. 2 is a sectional view, illustrative of a means for giving a movement to the feeding mechanism. Fig. 3 is a plan, and Fig. 4 is a sectional view at the line *x x*, illustrating my improvement as applied to the presenting of braids or strips to the sewing mechanism.

Similar marks of reference denote the same parts.

Sewing-machines have heretofore been made in which the feed has been effected by a lateral movement of the needle while in the cloth, the cloth being held by spring-pressure between stationary surfaces. The cloth has also been moved by the joint action of a roughened reciprocating surface, a yielding stationary surface, and the needle. One or two wheels or rollers have also been employed and moved progressively. A fourfold feed-motion has also been used, striking the feed against the cloth, moving it, withdrawing the feed, and returning. A reciprocating pawl-action pressure-foot has also been employed. These feeds have all been tested, and there are some objectionable features. Most all of them allow one of the thicknesses of the cloth to be forced along by the feed faster than the other, or else the needle or fabric is liable to injury and the feed is unreliable.

A sewing-machine feed has also been made with two spring-arms extending at right angles to the slide, to which they are affixed, and to which slide the movement is communicated by cams to feed the fabric through the agency of the movement of the arms laterally. When arranged in this manner there is considerable distance between the actuating-cam and the point where the feed clamps the fabric, and hence the feed will not be reliable, because

any looseness of the parts or lateral spring of the arms may vary the length of the stitch.

The nature of my said invention consists in a feeding-clamp having two surfaces, the first being part of the bed on which the fabric to be sewed rests, and the second portion of the feeding-clamp being above the fabric and connected around to the lower surface, so that the two form one instrument capable of grasping the cloth between the surfaces at the point where the fabric is to be sewed, in combination with the reciprocating mechanism that operates to move both portions of the feeding-clamp, by acting upon the lower portion of said clamp near the point where the sewing is performed, in order that the stitches may be made uniform, and not liable to variations in their length, from the parts springing or becoming loose from wear.

By means of this feed the material is kept perfectly smooth by the action of the clamp itself, and the feed moves back to take a new position while the cloth is in a state of rest and held by the needle. When the needle is drawn out of the fabric the feeding apparatus moves forward, carrying the material to be sewed, and also the guides, when such are used for operating upon braid, or for turning folds in hemming, or the guides employed in tucking or plaiting.

In the drawing, *a* represents the bed of any sewing-machine to which my feed may be applicable; *b*, the needle of such machine. *c* is the lower surface of the feeding-clamp, and *d* is the upper surface. These are connected together, so as to seize the cloth with the desired pressure and be moved together.

I have represented in Figs. 1 and 2 the plate *a'* as moving beneath the bed in slides *c'*, and connected by the column *e* with the surface *d*, so that they move together, and the motion is communicated by a revolving pin, *f*, in a slot made in the plate *a'*.

The lower clamp *c* is shown with a ring-formed bed, 2, around the portion of the clamp *c* that has the slot for the needle. This ring is fitted so as to turn freely and facilitate the turning of the cloth or other goods between the surfaces, and at the same time presents a sufficient bearing-surface for supporting the cloth.

The upper clamping-surface *d* might be similarly fitted with a ring, if desired.

The feeding-clamp shown in Figs. 3 and 4 is especially adapted to sewing braids or strips of material together, as in the manufacture of hats and bonnets, and can be applied advantageously to the sewing-machine patented by me July 14, 1868; but its use is in no manner limited to that machine, but may be applied with other sewing-machines.

The lower clamping-surface *c* is made as a plate, and the upper surface *d* is attached thereto. Both thicknesses of material to be united (if in the form of strips) might pass between the surfaces *c* and *d*. These plates may be guided by a rib or pin, *i*, on the bed of the machine entering the slot in the plate *c*; and the pin or other device employed for reciprocating the plate *c* may be applied at the slot *k*, or other convenient place.

The gage *l*, being made adjustable, is employed to determine the position of the edge of the fabric relative to the needle, and consequently the width of braid that is exposed, with uniformity, of each coil that is sewed on.

This device, as before named, is especially adapted to sewing braids for hats and bonnets, in which case the piece of braid passes in between the surfaces *c* and *d*, as shown; and the portion of the surface that has been sewed lies above the plate *d*, with its edge against the gage *o*, that is attached to *d*; and *p* is an auxiliary spring-presser, acting upon the surface of the previously-sewed article, (represented by the coiled crown-piece *q*, as shown.) The guide-pin *r* passes through the center of the coil of braid into the slot *s*, and into a slot in the bed beneath, so that it becomes a center upon which the braid turns as it is sewed up to form the crown-piece, and also a center upon which the clamp can swing as it is moved by the pin *k* in feeding the material. The braid, being held by the needle, is bent into a curve by the feed-plates *c* and *d* and gage *l* swinging back on the pin *r* previously to feeding the material forward, the next movement, and the gages *o* and *l* maintain a perfectly correct width of braid exposed each coil, and the center-pin *r*, constantly working back as the sewing progresses, causes the point on which the feed swings to be the center of the article being sewed, and at the same time the braid lies closely and correctly against the gages.

In sewing hats the crown-piece can be sewed as aforesaid, the braids will be laid together with great regularity in the spiral form by the guide before described, and when the side crown is to be sewed the same is performed by turning up the crown-piece edgewise and sewing the braid, as before, until the same is of the proper size. The crown will be wrong side out, and is to be turned and then the brim sewed upon its edge, the operations being performed as aforesaid. This feeding device may be fitted with any desired character of guides for turning hems, guiding tucks or plaits, braiding, or performing any other desired character of sewing.

The surface of the feeding-clamp may be smooth or more or less roughened, and the spring-pressure of the clamps may be adjusted, if desired.

I do not claim a sewing-machine feed formed of two surfaces, whether plain, circular, roughened, or flat, as these have before been employed, and they have in some instances moved together.

What I claim, and desire to secure by Letters Patent, is—

1. The feeding-clamp herein described, consisting of the upper spring-arm *d*, connected with the slotted sliding plate *a'*, supporting the lower feeding-surface *c*, when all are constructed, arranged, and operated as described.

2. The gage *l* for the edge of the material, combined with the reciprocating feed, having two moving and pressing surfaces, one on each side of the material, substantially as set forth.

3. The gage *o* and auxiliary presser *p*, in combination with the spring clamping-surfaces *c* and *d*, as and for the purposes set forth.

4. The guide-slot *s* and pin *r*, in combination with the feeding mechanism aforesaid, for the purposes set forth.

5. The feeding mechanism fitted to swing upon the pin that passes through the center of the coil of braid to be sewed, substantially as and for the purposes set forth.

In witness whereof I have hereunto set my signature this 18th day of August, A. D. 1868.

HIRAM PLUMMER.
